UNITED STATES PATENT OFFICE

124,740

DESIGN FOR A TIE RACK OR SIMILAR ARTICLE

Eugene M. Huber, Charleston, S. C.

Application May 7, 1940, Serial No. 92,203

Term of patent 7 years

To all whom it may concern:

Be it known that I, Eugene M. Huber, a citizen of the United States, residing at Charleston, in the county of Charleston and State of South Carolina, have invented a new, original, and ornamental Design for a Tie Rack or Similar Article, of which the following is a specification, reference being had to the accompanying drawing, forming part thereof.

Figure 1 is a top plan view of a tie rack or similar article, showing my new design.

Figure 2 is a front elevational view thereof.

Figure 3 is an end elevational view.

I claim:

The ornamental design for a tie rack or similar article, as shown.

EUGENE M. HUBER.
